UNITED STATES PATENT OFFICE.

ABEL HANSEN, OF PERTH AMBOY, NEW JERSEY.

WASHTUB.

1,112,700.

Specification of Letters Patent.

Patented Oct. 6, 1914.

Application filed May 18, 1914. Serial No. 339,297.

To all whom it may concern:

Be it known that I, ABEL HANSEN, a citizen of the United States of America, and residing at Perth Amboy, in the county of Middlesex and State of New Jersey, have invented certain new Improvements in Washubs, of which the following is a full and clear specification.

The object of the present invention is to produce a sanitary ventilated wash tub.

In wash tubs that are usually found in apartments with inclosing covers, much difficulty has been experienced from the lack of ventilation. With such tubs the tightly fitting covers confine disagreeable and dangerous gases, so that when the tubs are opened for use the odors are very objectionable and injurious.

The present invention comprises a one-piece compartment wash tub, having a ventilated overflow waste passage extending from the top to the bottom of the dividing partition between the compartments, with overflow communications with the compartment, and a triple waste drain in communication with said overflow waste passage and with the ordinary drain openings of the compartments of the tub. The overflow waste passage is open at the top for ventilation purposes. The tub cover is preferably made of reinforced sheet metal having radiating draining grooves leading to a depressed strainer outlet which is located when the cover is closed just over the open end of the overflow waste passage, so that said passage also acts as the drain outlet for the cover which serves in its closed position as a draining board for drying dishes.

In order that my invention may be fully understood I will first describe the same in reference to the drawing, and afterward point out the novelty more particularly in the annexed claims.

In the drawing.—Figure 1 is a perspective view of my improved wash tub, showing it provided with a combined cover and draining board in closed position; Fig. 2 is a vertical longitudinal sectional view of the tub taken on the line 2—2 of Fig. 1; Fig. 3 is a detail horizontal sectional view taken on the line 3—3, Fig. 2; Fig. 4 is a detail vertical transverse sectional view taken on the line 4—4, Fig. 2.

The present invention relates particularly

to a one-piece molded tub formed usually of porcelain or similar composition. The tub 1 has a central dividing partition 2 which is the same height as the side and end walls of the tub compartments. The partition 2 has a vertical passageway 5 extending through it from top to bottom, and communicating through overflow laterally extending openings 6 and 7 with the two tub compartments. These overflow openings 6 and 7 are arranged at the proper level to determine the extreme height of water contained in the tub compartments. The openings 6 and 7 are covered by strainer caps 10 held in place by the connecting rod or bolt 11 which is passed through one of the caps and threaded into the other in the usual manner, for holding the caps in place over the overflow openings. The rod or bolt 11 is formed with a flattened enlargement 12, centrally between its ends which normally rests in central position in the drain passage 5, for the purpose of partially obstructing said passage from above the overflow openings 6 and 7 to prevent pieces of soap or other objects passing down the drain passage, causing a stoppage of the waste.

The upper end of the passage 5 is formed with a flared or enlarged mouth 15 into which the drain of the cover leads.

20 is a sheet metal cover which is reinforced at its edges by the inclosed rod or wire 21. The cover is hinged to the back wall of the tub by means of rings or eyes 22 set into the wall of the tub, as shown clearly in Fig. 4. These hinge eyes 22 engage the reinforcing rod or wire 21 of the cover at the rear. The cover 20 is formed with a series of radiating draining grooves 25 which lead to a cup or depressed ventilating strainer pocket 26 adjacent to the rear edge 27 of the cover and located, when the cover is in closed position, just above the flared opening 15 of the drain passage 5, thus forming a draining board of the tub cover and utilizing the drain passage 5 as a common drain for the drain board cover and the tub compartments.

In the bottom of each tub compartment is formed an ordinary waste opening 30 adjacent to the dividing partition wall 2 and communicating with these waste openings 30 and the overflow drain 5 is a triple coupling 35 held in place by the usual threaded

flanged nipples 36, which afford seats for the usual stoppers 37. This drain coupling 35 leads into a common drain pipe 40 which is connected thereto in the usual manner. 45 5 are the water supply faucets.

It will be observed from the described construction that the tub compartments are always ventilated through the overflow passage 5 which is in communication with the 10 compartments, and is open at the top through the strainer cup 26. The overflow passage 5 extending from top to bottom of the partition 2 affords ready means for removing any obstruction in the drain or 15 three-way coupling, it being only necessary to remove the strainer caps 10 and passing a cleaning tool down through the passageway 5. It is not necessary to remove the permanently attached coupling 35 or other parts. 20 The combined draining board and tub cover

20 will be found of great convenience in serving its double purpose.

I claim:

1. A compartment wash-tub having a dividing partition wall formed with a drain 25 passage extending entirely therethrough, laterally extending overflow openings and an upwardly extending ventilating extension.

2. A compartment wash-tub having a dividing partition wall formed with a drain 30 passage extending entirely therethrough, and an upwardly extending ventilating extension, and a tight cover having a ventilating strainer.

ABEL HANSEN.
